UNITED STATES PATENT OFFICE.

CHARLES F. BUENTE, OF ALLEGHENY, PENNSYLVANIA.

FIREPROOF FLOOR CONSTRUCTION.

SPECIFICATION forming part of Letters Patent No. 728,857, dated May 26, 1903.

Application filed April 27, 1900. Renewed October 28, 1902. Serial No. 129,176. (No model.)

To all whom it may concern:

Be it known that I, CHARLES F. BUENTE, of Allegheny, in the county of Allegheny and State of Pennsylvania, have invented a new and useful Improvement in Fireproof Floor Construction, of which the following is a full, clear, and exact description, reference being had to the accompanying drawings, forming part of this specification, in which—

10 Figure 1 is a vertical sectional view, taken at right angles to the main floor-beams, of a fireproof floor construction formed in accordance with my invention. Fig. 2 is a partial vertical cross-section at right angles to that of Fig. 1. Fig. 3 is a partial cross-section showing another form of my invention in connection with ordinary metal main beams. Fig. 4 is a detail view of the web member I preferably employ; and Fig. 5 is a view similar to Fig. 2, showing a modified construction.

25 My invention relates to the construction of fireproof flooring, and is designed to provide a cheap and simple construction which shall be of great strength, may be easily adapted to different arrangements of main beams, and may, if desired, be built in place without the use of temporary supports.

30 In the drawings, referring to the form of Figs. 1 and 2, 2 represents a side wall having the usual supporting angle-iron 3, and 4 is a main floor-beam, which I have shown as composed of concrete filled in around and inclosing a series of web members 5. These web 35 members consist of a lower tension member 6, which may be formed of a metal bar or rod or a wire rope, and a latticed construction extending upwardly therefrom and preferably formed of interwoven wires 7. The preferred 40 construction of this web member is shown in Fig. 4.

The main floor-beams are connected to each other and to the walls by transverse beams 8, also of concrete, and each containing a web 45 member 9, similar to that shown in Fig. 4.

The concrete of the transverse beams is preferably formed integrally with that of the main beams where the construction of Fig. 1 is employed, and the concrete of the trans- 50 verse beams is integrally joined over the tops of permanent refractory centers 10. These

arched-shaped hollow centers 10 are preferably provided with a central web 11 and are placed between the web members around which the concrete transverse beams are 55 formed. The wooden sleepers 12 are placed directly over the web members and preferably secured thereto by a staple 13 or in any other desirable way, the concrete being filled around the lower portions of the sleepers, so 60 as to embed them in the floor.

In building the floor a temporary under-structure is provided upon which the refractory centers are placed, and the web members being placed in their proper positions and se- 65 cured to sleepers the concrete is supplied be- 70 tween and over the centers and around all the web members, thus forming the main beams and the transverse supporting-beams, each transverse beam having a web or lat- 75 ticed strengthening-grid. Instead of using the temporary supports the refractory cen- 80 ters may be supported from the latticed mem- 85 ber by means of hook-bolts 14, which may be hung on the lower tension member 6 and are 75 provided with lower plates, which support the meeting edges of adjacent tiles or cen- 90 ters. The centers being notched slightly are hung in place, and the concrete may then be supplied and the beams formed, after which 80 the bolts and supporting-plates may be re- 95 moved.

Instead of using concrete main beams which are formed in place I may use the ordinary main beams 15, as shown in Fig. 3, the con- 85 crete being filled in between the flanges and the tension members of the transverse webs on each side being connected together by stirrup 16, which is preferably formed of spring metal, so as to put a slight tension on 90 the webs. In both forms the end portions of the refractory center next to the wall or the main beams are preferably cut back or bevel- 95 ed, so as to allow the concrete of each beam to be integrally connected at these points, as shown in Figs. 1 and 3.

Instead of having the concrete of adjacent transverse beams integrally joined over the tops of the hollow centers I may use sepa- 100 rated transverse concrete beams, as shown in Fig. 5. In this form the refractory centers 10 are provided with upwardly-projecting

flanges 17, which form the sides of the upper part of the concrete beam 18, thus separating them and leaving spaces over the hollow centers for the reception of piping or wires. In 5 this form I also preferably use the web or latticed central grid 19 for each concrete beam.

When a tile flooring is used, the wooden sleepers are dispensed with.

The advantages of my invention will be 10 apparent to those skilled in the art, since a simple construction of great strength is afforded which can be easily formed in place and can be built without the use of metal connections between the main beams. The 15 use of the concrete beams with the central strengthening-grid insures a strong structure, while the hollow tile or centers reduce the weight and cheapen the cost. The tiles serve to protect the concrete from heat, thus 20 doing away with the objection to ordinary concrete constructions. The formation of the strengthening-grids may be widely varied, and many other changes may be made in the form and construction without departing 25 from my invention.

I claim—

1. In fireproof floor construction, a series of concrete beams, having floor-sleepers embedded in their top portions and extending

longitudinally thereof; substantially as de- 30 scribed.

2. In fireproof floor construction, a series of concrete beams with reinforcing metallic grids, and having arched connecting-tops forming compression members and refractory 35 centers between the beams; substantially as described.

3. In fireproof floor construction, a series of transverse parallel concrete beams, each having a lower metallic tension member, and 40 a latticed construction extending upwardly therefrom and embedded in the concrete, and wooden sleepers partially embedded in the concrete and extending longitudinally of the lattice-work; substantially as described. 45

4. In fireproof floor construction, wooden sleepers having depending web members secured thereto and embedded in concrete, and supports upon the web members arranged to hold the hollow refractory centers in place; 50 substantially as described.

In testimony whereof I have hereunto set my hand.

CHARLES F. BUENTE.
